UNITED STATES PATENT OFFICE.

HENRY J. DAVIES, OF BROOKLYN, NEW YORK.

DESIGN FOR CLOCK-FRONTS.

Specification forming part of Design No. 11,181, dated May 6, 1879; application filed April 10, 1879.
[Term of patent 7 years.]

To all whom it may concern:

Be it known that I, HENRY J. DAVIES, of the city of Brooklyn, in the county of Kings and State of New York, have invented a new and original Design for the Fronts of Clocks, of which the following is a description, reference being had to the accompanying photographic illustration, making part of this specification.

The general form of the clock-front is that of a horseshoe, A, arranged to occupy an erect position with its open end undermost, and containing within it the dial B of the clock, which forms a central figure within the closed end and sides of the shoe. Said figure of the shoe is embellished by ornaments b, representing nail-heads.

Surrounding the shoe A is an ornament representing a horse's head, C. This ornament C on top of the clock-front is enriched or beautified by ornaments representing harness, including a saddle, c, having attached stirrups d, a bridle, e, and a whip, f.

What I claim as my invention is—

1. The design for the front of a clock, comprising the figure of a horseshoe having contained within it the dial of the clock, substantially as herein described, and as illustrated in the accompanying photographic illustration.

2. The design for the front of a clock, comprising the figure of a horseshoe, A, having contained within it the dial B of the clock, and surmounted by the figure of a horse's head, C, substantially as described, and as shown in the accompanying photographic illustration.

3. The design on the top of the clock-front, comprising a horse's head, and a saddle with stirrups, bridle, and whip, essentially as described, and illustrated in the accompanying photographic illustration.
